(57) **CLAIM**

We claim the ornamental design for a combined panel trim and flashing, as shown and described.

DESCRIPTION

FIG. 1 is a perspective view of a first embodiment of a combined panel trim and flashing;

FIG. 2 is a perspective view of the first embodiment of a combined panel trim and flashing, the broken lines are for illustrative purposes only and form no part of the claimed design.

FIG. 3 is a top view thereof of the first embodiment;

FIG. 4 is a bottom view thereof of the first embodiment;

FIG. 5 is a right view thereof of the first embodiment, the left view of the first embodiment being a mirror image of the right view;

FIG. 6 is a front view thereof of the first embodiment;

FIG. 7 is a rear view thereof of the first embodiment; and,

FIG. 8 is a perspective view of a second embodiment of a combined panel trim and flashing, the only difference being the bottom groove orientation and arcuate shape of the bottom panel.
